UNITED STATES PATENT OFFICE

ROBERT FINDLAY, OF JAMAICA, NEW YORK

BATH SPRAY

Application filed September 5, 1931. Serial No. 561,408.

This invention relates generally to bath showers or sprays and has particular reference to devices in that general class which are portable and which are intended to be readily connected to the faucet of a bath tub or similar source of water supply when it is desired to use it.

One of the objections to prior devices of the kind is that it is difficult to use them without an objectionable splashing of water.

One of the objects of this invention is to provide a spray device which will leave the hands of the user free and by which the water is delivered in such a way that there will be a minimum amount of splashing.

Another object is to provide a device which can be sold at a low price but which will, nevertheless, be sturdy and efficient in operation.

With the foregoing and other advantages in view the invention consists in a novel combination and relation of elements, the novel features of which are pointed out in the claims and a preferred embodiment of which is hereinafter described with reference to the drawing accompanying and forming a part of this specification.

In the drawing:

Fig. 1 is a top plan view of the spray device with portions cut away to show the interior construction of some of the tubes.

Fig. 2 is a section substantially on the line 2—2 of Fig. 1 looking in the direction of the arrows.

Fig. 3 is a section along the line 3—3 of Fig. 1.

Fig. 4 shows how the device appears when in use.

The form of the device shown in the drawing comprises sections 10 and 11 which are oppositely curved and which contain perforations 12 so positioned that the water is directed inwardly toward the person of the user. At the same time the angle at which the water is directed inwardly is not sufficiently great to cause what might be termed a re-bound of the water away from the body sufficient to cause objectionable splashing.

The ends of the spray sections 10 and 11 are connected together by unperforated tubes 13

and 14. The two tubes last mentioned may be of any desired form, but it is preferred to curve them so that they will engage the shoulders of a user in such a way as to aid in maintaining the device as a whole in position. 55 The tubes 13 and 14 should also be so formed or constructed as to hold the spray tubes 10 and 11 away from the person of the user. It is preferred to have upstanding end portions 15 and 16 connected as at 17, Fig. 3, to the 60 ends of the spray tubes 10 and 11. The portions 15 and 16 may be of any desired height, but it is preferred to have them only of sufficient height to insure against the spray openings 12 coming in contact with the body 65 and thereby interfering with the flow of water.

One of the spray tubes is provided with a connection 18 containing a channel 19 in alignment with an orifice in the wall of the 70 spray tube 11. It is preferred to have the connection 18 fast on the spray tube 11 but it is obvious that the connection might be rotatable on the tube and operate to serve as a valve for conveniently shutting off the 75 water supply. The connection 18 has an extension 20 to receive one end of a flexible tube 21. This flexible tube has at its other end any suitable device for connecting the tube to the faucet of a bath tube or any other 80 convenient source of water supply.

By providing the unperforated sections 13 and 14 the water is not directed against the curves of the shoulders or the outside of the arms so that the device can be used in a bath tub without objectionable splashing even though the user is standing in the tub.

It is obvious that because of the flexible tube connection and the construction as a whole that the device may be used as a hand 90 spray where something more than the shoulder spray is desired.

While a preferred embodiment has been described in detail it is not the desire to be limited to those details. In fact it will be 95 obvious to those skilled in the art that the advantages of the improved device may be obtained by modifications and changes which nevertheless come within the scope of the claims which follow.

What I claim is:

1. A device of the character described comprising a pair of oppositely curved spray tubes, unperforated tubes connecting the ends of the spray tubes and formed to engage the shoulders of a person, and connections for supplying water to the interiors of the spray tubes and connecting tubes.
- 10 2. A device of the character described comprising a pair of oppositely curved tubes having spray perforations in their walls positioned to direct water inwardly toward the person, tubes connecting the two spray tubes at their ends and forming conduits between the spray devices, said connecting tubes being constructed to hold the spray devices out of contact with the person, and devices for connecting the device to a source of water supply.
- 15 3. A device of the character described comprising a pair of outwardly curved spray tubes, a pair of tubes connecting the ends of the spray tubes and forming conduits between the spray tubes, said connecting tubes being curved to engage the shoulders of a person and having their ends formed to support the spray tubes out of contact with the person, and means for connecting the device to a source of water supply.
- 20 4. A device of the character described comprising a pair of oppositely curved tubes perforated to form two spray devices, tubes connecting the two spray devices and forming conduits connecting said devices, said connecting tubes being curved to engage the shoulders of a person and having their ends upturned to hold the spray devices away from the person, and connections for supplying water to the perforated tubes and the connecting tubes.
- 25 40 In testimony whereof I hereto affix my signature.

ROBERT FINDLAY.
